COSTUMER

Wilbert F. Comstock, Union City, Pa.

Application April 29, 1955, Serial No. 35,735

Term of patent 7 years.

(Cl. D33—8)

I claim:

The ornamental design for a costumer, as shown.
